UNITED STATES PATENT OFFICE.

HENRY RAYMOND MILLER, OF LEBANON, PENNSYLVANIA.

DESIGN FOR A SEWING-CABINET.

No. 39,918.

Specification for Design.

Patented April 13, 1909.

Application filed January 25, 1909. Serial No. 474,184. Term of patent 7 years.

To all whom it may concern:

Be it known that I, HENRY RAYMOND MILLER, a citizen of the United States, residing at Lebanon, in the county of Lebanon and State of Pennsylvania, have invented a new, original, and ornamental Design for a Sewing-Cabinet, of which the following is a specification, reference being had to the accompanying drawing, forming part thereof.

The figure is a perspective view of a sewing cabinet, showing my new design.

I claim:

The ornamental design for a sewing cabinet, as shown.

HENRY RAYMOND MILLER.
